UNITED STATES PATENT OFFICE.

FRANK F. FORSHEE, OF FLINT, MICHIGAN, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

ADJUSTABLE-HANDLE IRON.

Application filed October 25, 1921. Serial No. 510,395.

My invention relates to electrically heated apparatus and particularly to electrically heated irons and it has for one of its objects to provide a handle for an electric iron that shall have a single pivotal mounting on the iron.

Another object is to provide a mounting for a flat-iron handle of the above indicated character that shall serve as a supporting means for a terminal and a connecting-plug guard.

This application is a continuation, in part, of my copending application, Serial No. 423,562, filed Nov. 12, 1920.

15 In practicing my invention, I provide an electrically heated iron having a cover member, a metal handle strap secured to the rear end of the cover member, a handle support, of substantially U-shape, and a terminal and a connecting-plug guard secured to the handle strap.

A handle is pivotally and adjustably mounted on the handle support, a spring-biased clamping means on the handle operating with a plurality of notches on the handle support to clamp the handle in any one of a number of predetermined angularly disposed positions relatively to the body portion of the iron.

30 In the single sheet of drawings,

Figure 1 is a view, partly in longitudinal section and partly in side elevation, of an electrically heated iron comprising the device embodying my invention, and

35 Fig. 2 is a top plan view of an iron embodying my invention.

An electric iron, designated generally by the numeral 10, comprises a working member or sole plate 11, top plate 12 and an electric heating element 13 which is clamped between the sole plate and the top plate by means of a plurality of clamping screws or bolts 14. The members 11, 12 and 13 constitute what may be termed the body portion 40 of the iron. A cover member 14^a is located over the top plate 12 and may be suitably secured in its proper operative position upon the body portion of the iron by means of a bolt or screw 15.

50 The heating element 13 may be of any

suitable construction usually employed in electrically heated irons and is not described in detail as it forms no particular part of my invention. The ends 16 of the resistor of the heating element 13 may be secured to 55 terminal strap members 17 by means of suitable screws or bolts 18. The terminal-strap members may be of any suitable or desired shape and are here illustrated as substantially of L-shape, one leg thereof extending 60 under the overhanging rear end of the top plate 12 and being secured thereagainst by means of a screw 19, suitable insulating members 21 and 22 being located on each side of the terminal plate to insulate the 65 same from the top plate 12 and the screw 18. Contact terminals 23 are secured to the terminal straps 17 and project outwardly through a suitable opening 24 at the rear of the cover member 14^a, an insulating member 25 being provided to maintain the terminals 23 and the terminal straps 17 in proper operative positions relatively to the cover member 14^a and the opening 24. If necessary, a plate 26 of suitable insulating 70 material may be placed inside of the rear of the cover 14^a to insure that the terminal straps 17 do not operatively engage the cover and become short circuited thereby 75 during the operation of the iron.

80 An elongated handle strap 27 has its inner end projecting through an opening 28, which is located immediately in front of the opening 24 in the cover and is secured to the cover by a suitable rivet 29. The rear portion of the cover member is pressed upwardly to provide a suitable flat surface 30, through which the contact terminals 23 may project, the front angularly inclined surface of the upwardly pressed portion being 85 indicated by 30-A. The outer portion of the handle strap 27 extends upwardly and rearwardly from the cover of the iron.

90 A handle-supporting member 31 comprises a portion of substantially U-shape in 95 lateral section, the middle part of which is substantially co-extensive with the outer and rear part of the handle strap. A portion 32 of the handle-supporting member 31 extends forwardly of the portion of U-shape 100

and is secured against the outside of the cover member by means of the rivet 29 hereinbefore described as securing the handle strap against the cover member. An extension 33 of the member 31 is return-bent 5 around the outer end of the handle strap 27 to more rigidly secure it thereon, a suitable screw 34 being provided, at substantially the middle of the member 31, to secure it 10 against the handle strap. A plurality of notches 35 are provided in the outer arcuate edge of the portion of U-shape for a purpose to be hereinafter set forth more in detail.

A handle 36, of any suitable insulating 15 material, is provided with an axial hole 37 therethrough having an enlarged outer end portion 38 and an enlarged inner end portion 39. A metal bushing 41 is located in the enlarged portion 39 and is provided 20 with a threaded axial opening 42. The end of a long screw 43, the head of which lies in the portion 38 of the hole 37, screws into the opening 42, this construction serving to 25 securely clamp the member 41 in its operative position in the inner end of the handle 36. One end of a screw-threaded stud 44 is screwed into an opening 42a in the outer end of the bushing 41 and has its other end secured in a collar 45 which is located on a 30 pin 46 mounted in the two side walls of the portion of U-shape of the member 31. The collar 45 has a turning movement on the pin 46 and the stud 44 is suitably locked on the collar 45 to prevent its becoming disengaged 35 therefrom as the handle 36 is turned thereon.

A clamping member 47, substantially of 40 channel section, is located at the inner end of the handle 36 immediately adjacent the outer end of the bushing 41 and surrounding the stud 44, the distance between the outer edges being such that they will register with, and operatively engage, two of the notches 35, hereinbefore described. A coil 45 spring 48 surrounds the stud 44 and tends to force the member 47 out of the notches 35. By turning the handle 36 on the stud 44 the spring 48 may be compressed and the outer edges of the member 47 caused to engage the notches in the member 31 to lock 50 the handle in any one of a number of predetermined angularly disposed positions relatively to the body portion of the iron, several positions of the handle being illustrated by broken lines in Fig. 1.

55 A terminal and connecting-plug guard 49 is suitably secured against the under surface of the handle strap 27 by means of the screw 34, which holds the handle-supporting member 31 in its operative position on 60 the handle strap. A connecting plug 51, in which is located the end of the supply-circuit cord 52, fits within the guard 49 and permits of suitably energizing the heater element of the iron.

65 If it is assumed that the handle is in the

position illustrated by the full lines in Fig. 1 and it is desired to change this position to permit of using the iron in actual operation, the operator may give the handle a rotating movement on its longitudinal axis in such 70 direction as to cause the handle to move outwardly on the stud 44, the clamping member 47 being caused to follow the handle by reason of expansion of the coil spring 48. As soon as the outer edges of the clamping 75 member are disengaged from the notches 35, the handle member may be given a turning movement on the pin 46 to any one of a number of positions, two of which are illustrated in Fig. 1. To lock the handle in 80 any desired position, it is only necessary to turn the handle on the stud 44 in the opposite direction to that in which it was previously turned, which compresses the spring 48 and causes the clamping member 47 to 85 engage notches 35 and lock the handle in the selected position.

As the completed device occupies the least volume when the handle is in the position illustrated in the full lines of Fig. 1, it may 90 be shipped with the handle in this position, and stored away when not in actual use and the operator can quickly adjust the handle to any one of a number of angular positions, as may be desirable by reason of the 95 height of the ironing surface relatively to the operator's hands. It is also possible to quickly change the angular position of the handle relatively to the iron during the 100 working period to rest the operator's hand and wrist, if desired.

Various modifications may be made in the device embodying my invention without departing from the spirit and scope thereof, and I desire that only such limitations shall 105 be placed thereon as are imposed by the prior art or are specifically set forth in the appended claims.

I claim as my invention:—

1. In an electric iron in combination, a 110 body portion, a cover member therefor, a handle strap secured to said cover member, a handle support secured to said handle strap, and a handle having a single pivotal mounting on said handle support.

2. In an electric iron, in combination, a body portion comprising a heating element and contact terminals therefor, a cover member secured to the body portion, a handle strap secured to said cover member, a handle support, substantially of U-shape, secured to said handle strap and to said cover member, and a handle having a single pivotal mounting on said handle support. 120

3. In an electric iron, in combination, a 125 body portion, a cover member therefor, a handle support mounted on said cover member, of substantially U-shape and having a plurality of spaced notches thereon, a pin mounted in said support, a collar located on 130

said pin and having a turning movement thereon, a handle having a screw engagement with said collar, a clamping means on said handle for co-operating with said notches in said handle support to hold said handle in a predetermined angular position relatively to said iron and resilient means

tending to hold said clamping means out of engagement with said notches in said handle support.

10

In testimony whereof, I have hereunto subscribed my name this 12th day of Oct., 1921.

FRANK F. FORSHEE.
